Primary Examiner—Ted Shooman*Assistant Examiner*—Richelle Shelton*Attorney, Agent, or Firm*—Ralph S. Branscomb[57] CLAIM

The ornamental design for a jewelry organizer, as shown and described.

DESCRIPTION

FIG. 1 is front elevation view of a jewelry organizer showing my new design, the rear elevation view being identical;

FIG. 2 is a top plan view thereof;

FIG. 3 is a bottom plan view thereof;

FIG. 4 is a right side elevation view thereof, the left side elevation view being identical;

FIG. 5 is a perspective view of the bottom tray of FIG. 1;

FIG. 6 is a perspective view of the left top tray of FIG. 1;

FIG. 7 is a perspective view of the right top tray of FIG. 1;

FIG. 8 is a perspective view of the right central tray of FIG. 1;

FIG. 9 is a perspective view of the left central tray of FIG. 1;

FIG. 10 is an exploded right side elevation view of FIG. 1, the exploded left side elevation view being identical;

FIG. 11 is a top plan view of the bottom tray of FIG. 1; and,

FIG. 12 is a front elevation view thereof, the rear elevation view being identical.

The trays shown in FIGS. 5-9 and 12 are shown separately for clarity of illustration.
